[57] CLAIM

The ornamental design for a cup or the like, substantially as shown and described.

DESCRIPTION

FIG. 1 is a top perspective view of a cup or the like showing my new design;

FIG. 2 is a rear elevational view thereof;

FIG. 3 is a top plan view thereof;

FIG. 4 is a side elevational view thereof;

FIG. 5 is a bottom plan view thereof; and

FIG. 6 is a cross-sectional view thereof taken along line 6—6 of FIG. 2.

The design is characterized by a horizontal projection positioned proximate the midpoint of the cup sidewall with a distinctively curved interconnection between both the upper and lower sidewall extents and a handle whose horizontal arms are of a trapezoidal shape and whose outer surfaces exhibit a slight curvature.
